DESIGN FOR A RAZOR BLADE HOLDER FOR SHARPENING

Edward Olszewski, Detroit, Mich.

Application August 19, 1944, Serial No. 114,938

Term of patent 14 years

(Cl. D37—1)

To all whom it may concern:

Be it known that I, Edward Olszewski, a citizen of the United States and resident of the city of Detroit, county of Wayne, and State of Michigan, have invented a new, original, and ornamental Design for Razor Blade Holders for Sharpening, of which the following is a specification, reference being had to the accompanying drawing, forming part thereof.

Fig. 1 is a side elevational view of a razor blade holder for sharpening showing my new design;

Fig. 2 is an end elevational view of said holder; and

Fig. 3 is a bottom plan view thereof.

I claim:

The ornamental design for a razor blade holder for sharpening, as shown.

EDWARD OLSZEWSKI.
